UNITED STATES PATENT OFFICE.

ROBERT C. PIERCE, OF AKRON, OHIO, ASSIGNOR TO THE B. F. GOODRICH COMPANY, OF NEW YORK, N. Y., A CORPORATION OF NEW YORK.

DRIVING AND STOPPING MECHANISM.

1,420,744.

Specification of Letters Patent. Patented June 27, 1922.

Application filed September 12, 1921. Serial No. 499,961.

To all whom it may concern:

Be it known that I, ROBERT C. PIERCE, a citizen of the United States, residing at Akron, in the county of Summit and State of Ohio, have invented a certain new and useful Driving and Stopping Mechanism, of which the following is a specification.

This invention relates to driving and stopping mechanisms for winding machines, especially such as are adapted for ring winders, and is mainly an improvement upon machines of the character shown in United States Patent 1,294,160, issued February 11, 1919, to A. C. Pratt, for making grommets or bead rings for pneumatic tires, wherein a wire drawn from a spool carried by a ring winder is fed into an annular, channeled form or guide-member, by a wire feeding device also carried by the ring winder, the wire being pushed circumferentially around in the form until several convolutions of wire, constituting a grommet, lie within the form. Such a grommet, as taken from the machine, is shown in Fig. 6 (Sheet 2) of the drawings herein and preferably consists of a single, continuous wire comprising a semi-circular core strand A, six convolutions B of the same wire, wound helically about said core strand and about the corresponding empty core space throughout the rest of the circle, and a length of straight wire C adapted to be forced in between the convolutions to fill the core space and complete the core.

In prior machines of this character, there has been used a cam drum for timing the operation of the ring winder, which lays the wire in helical convolutions, and of the wire feeding mechanism, carried by the ring winder, which feeds the wire into the form, and a cone brake has been used to stop the ring winder, but in such devices the stopping point of the ring winder is not accurately predetermined, and it therefore usually requires to be turned by hand to bring its slot into position for removal of the work, and more or less than the desired amount of helical wire frequently is fed into the form. Moreover, the cam drum has been driven, step by step, by a pawl and ratchet mechanism, and the machine has been adapted for different sized bead rings by changing the stroke of the pawl to vary the speed of the cam drum, each size of bead ring thus re-

quiring a different speed of the drum, which is difficult accurately to obtain, by the means stated, and only such speeds can be obtained as correspond to the number of ratchet teeth which may be embraced in the stroke of the pawl,—that is, the drum in such a device is capable only of the speed corresponding to a pawl-stroke of one tooth, or multiples thereof corresponding to two or more teeth.

My general object is to provide improved means for controlling the operation of such a machine. More specific objects are to provide improved means for stopping different parts of the machine in predetermined relation to each other and to the work, and to provide such means adapted for minute adjustment for operations of different length. Further objects are to provide an improved timing mechanism wherein the length of operation may be predetermined by linear measurement, instead of varying the speed of a part, and automatic means for resetting the machine after each complete operation.

Of the accompanying drawings:

Fig. 1 is a rear elevation, with parts broken away, of a preferred embodiment of my invention as applied to a machine for winding grommets.

Fig. 2 is a fragmentary side elevation of parts of the stopping mechanism.

Fig. 3 is a diagram of the electric system.

Fig. 4 is an end elevation of the machine, with parts broken away.

Fig. 5 is a fragmentary sectional view of the cam drum showing an adjustable weight for automatically positioning said drum.

Fig. 6 is an elevation of a grommet as produced by a machine such as that shown in the drawings.

Fig. 7 is a front elevation of the machine, with parts broken away, showing the cam drum in stopped position at the completion of an operation.

Fig. 8 is a view, with a part broken away, of certain parts in inoperative position, from the same viewpoint as Fig. 7.

Fig. 9 is a front elevation, with parts broken away, showing the cam wheel, the brake mechanism, and parts associated therewith, in starting position.

Fig. 10 is a front elevation of parts of the device, including those shown in Fig. 2, the same being shown in actual position with relation to Fig. 9.

Fig. 11 is a section on line 11—11 of Fig. 9.

Fig. 12 is a perspective view of a part of the cam drum and a device co-acting therewith.

Referring to the drawings, 10 is a frame upon which is mounted in a horizontal plane a form 11 in the shape of an incomplete annulus, provided with a channel 12 (Fig. 10) adapted to be opened for removing the finished work. Encircling the space between the open ends of said form is a peripherally-supported ring-winder 13 having a driving gear 13^a. Said ring-winder carries a wire-supply spool 14 journaled in a head 14^a and two pairs of wire-feeding rollers 15, 15, whose shafts 15^a are driven through gearing 15^b, a shaft 15^c, and gearing 15^d from a bevel gear 15^e which meshes with a bevel gear 16 on the rear end of a sleeve 16^a journaled within the ring-winder, said sleeve having at its front end a spur gear 16^b which is rotated in the same direction as the winder, but at a higher speed, by means 15 presently to be described. The ring-winder 13, its gear 13^a, the sleeve 16^a and its two gears 16 and 16^b are all radially slotted for passing the grommet out of the machine. The rollers 15 are adapted to feed wire from 20 the spool 14 into one of the open ends of the guide-channel 12. 17 is a spiraling die or "quill," mounted upon the ring-winder and formed with a helical channel therethrough, adapted to guide the wire from the feed-rollers 15 into the channel 12, and, when 25 the ring-winder is driven, to impart a permanent helical form to the wire as it passes through said die. It heretofore has been known that while such helical form is given 30 to the wire when it is fed through the die with the ring-winder in motion, the straight wire for the core of the bead ring may be obtained by feeding the wire through the die while the ring-winder is stopped, the 35 wire which has passed through the die being prevented from rotating on its own axis, the wire in this case not being permanently deformed, although passing through the die.

It is thus desirable, for rapid production, 40 that at the end of the feeding of the spiraled convolutions the ring-winder be stopped while the wire-feeding rollers continue to be driven, to feed enough straight wire for the last half core of one bead ring and the 45 first half-core of the next bead ring, while the straight wire is prevented from turning upon its own axis by its integral connection with the body of the grommet.

The form 11 is then opened, the straight 50 wire cut at an appropriate point and the grommet in the shape shown in Fig. 6 is removed. The form is then closed with the first half-core of the second ring lying therein, the ring-winder is started, and the 55 spiraled convolutions are laid. The last

half-core C of the grommet is worked into place between the spiral turns by hand.

For a perfect grommet, extreme accuracy is desirable in the lengths fed respectively of the spiraled and non-spiraled wire. It 70 is therefore important that the stopping of the winder (while the wire-feed continues), representing the change from spiraled to straight wire, be timed with great accuracy, and likewise the stopping of the wire-feed 75 when the straight wire for the two half-cores has been fed. This necessitates not only an effective brake-mechanism for the ring-winder, but means for delicately adjusting the application of the brake, and said means 80 should be adaptable for bead rings of different sizes. It is also desirable that the ring-winder be stopped with the radial slot thereof within the gap in the ring-winder support, and that the sleeve 16^a be stopped 85 thereafter, at the end of the feeding of straight wire, with its slot in registry with that of the ring-winder, to facilitate the removal of the work.

Means for driving the ring-winder 13 and 90 the wire-feeding rollers 15 comprises a drive shaft 18 provided with a sprocket 19 and drive chain 20 (Fig. 1), said drive shaft having secured thereon gears 21, 22 (Figs. 4 and 7) respectively meshed with gears 95 23, 24 loosely journaled on respective shafts 25, 26, the gear 23 being provided with a jaw clutch member 27 (Figs. 4 and 11). 26^a is a hand wheel secured upon the front end of the shaft 26, for turning the sleeve 100 16^a to bring its slot into registry with that of the ring-winder 13 in case of imperfect operation of the parts hereinafter described, or in other emergency, to permit the removal of the work. Secured upon the rear 105 ends of said shafts 25, 26, are gears 28, 29, respectively meshed with the gears 13^a and 16^b, heretofore mentioned (Fig. 7). Slidably keyed upon shaft 25 is a jaw clutch member 30 (Figs. 4 and 11), provided with a spring-projected shipper slide 31, the spring being shown at 31^a in Fig. 11, said clutch being adapted for driving and releasing the ring-winder.

Secured upon the shaft 25 adjacent the 115 gear 28 is a brake-drum 33 provided with a brake-band 34, the movable end of which is connected with the lower arm of a compound lever 35 secured to a rock-shaft 36 journaled in the frame of the machine, said 120 lever having an upper arm in the form of a lever member 37 pivoted at 37^a to oscillate in the plane of the rock-shaft 36. This member is provided with a roller 38 at its outer end adapted, when said member is 125 operatively positioned, to engage a spring-backed brake-shoe 39, pivoted upon the spool-support 14^a of the winder, as the latter revolves past said roller. Said brake-shoe preferably is curved, as shown, and so posi- 130

tioned as to produce a braking action of progressively increasing force and ultimately a positive stop.

The shaft 36 is provided with a lug or finger 40 pressed by a spring 41 to hold the brake-band 34 normally in a slack condition. Said shaft 36, at its end opposite the brake-lever 35, is forked, and fulcrumed at 42^a in said end is a lever 42 having its lower end associated with a cam wheel presently to be described and its upper end connected, by a telescopic link 43 containing a compression spring 44, with the lever 37, for throwing the roller 38 into the path of the brake-shoe 39 and withdrawing it therefrom. A tension spring 45 connects the lower arm of the lever 42 with a part of the frame of the machine to hold the roller 38 normally out of said path.

20 The mechanism for actuating the aforementioned clutch and brakes comprises a cam drum 46 provided with a gear 46^a on its periphery with which meshes a gear pinion 47 secured upon a common shaft 48 with a hand-crank 49 and a worm gear 50, the latter being driven by a worm 51 upon a shaft 52 journaled in a sleeve 53 pivoted upon the drive shaft 18. 54, 55 are bevel gears secured upon the drive shaft 18 and the worm shaft 52, respectively, for driving the latter. An extension 53^a on the sleeve 53 rests on a cam 56 which is pulled by a spring 56^a into the worm-meshing position shown in Fig. 1 and is adapted to be turned 35 in the opposite direction by a treadle-rod 57 and treadle 57^a to allow the worm to drop out of mesh as indicated in Fig. 8, a manually-releasable latch 53^b serving to retain said sleeve in the latter position.

40 The cam drum 46 is provided with a cam member 58 formed with an inclined face 58^a (Figs. 4, 7 and 9), adapted to crowd the lower end of the lever 42 to the left, as viewed in Fig. 7, to turn the shaft 36 and 45 tighten the brake-band 34, and with a laterally-acting, oblique face 58^b adapted subsequently to crowd the lever 42 to the right, as viewed in Fig. 4, to throw the roller 38 into the path of the brake-shoe 39, this cam 50 being adjustable circumferentially on the drum to time its action.

Said cam drum 46 is also provided with an elongated, laterally-acting cam 59, shown as being adjustable circumferentially on the drum to time its action, although I prefer to leave it in a fixed position and adapt the machine for different sized rings by adjusting other members hereinafter described. Said cam 59 is adapted to actuate the ship- 60 per slide 31 to throw out the driving clutch member 30 of the ring-winder. Also upon the cam drum 46 is a circumferentially adjustable power stopping cam lug 46^b adapted to open an electric switch 46^c to shut off the 65 power when the desired length of straight

wire has been fed into the form 11, and immediately thereafter to close a normally open switch 46^e by contact with a lever 46^f to actuate a hereinafter described stopping mechanism for the wire-feeding means. The 70 cam drum is large enough to control, during less than a complete revolution, the several operations incident to one complete wire-feeding movement of both straight and helical wire, even for the large sized beads, 75 so that said drum at the end of each complete operation, while free from the general driving mechanism, requires to be turned forward from its stopped to its starting position for the next wire-feeding movement. 80

The starting position for the cam drum 46 is determined by a circumferentially adjustable stop 61 (Figs. 1, and 7) secured to the cam drum 46 and adapted to be engaged by a lever 60 provided with a stop lug 60^a 85 and a spring-pressed latching pawl 60^b when the drum reaches the starting position. Said lever 60 is pivoted at 60^c and is so positioned that the rear end of it is pressed downward by the treadle 57^a, against the 90 action of a spring 80^a, whenever said treadle is depressed, raising the opposite end of said lever into position for its lug 60^a to engage the stop 61.

The cam drum 46 is provided with a radially and angularly adjustable weight 46^d (Figs. 5 and 7) so fixed upon the cam drum that when the entire machine is stopped, by the cam lug 46^b actuating the switches 46^c, 46^e, said weight will be on the descending 100 side of the drum 46 in such position that it will automatically turn the drum forward to starting position, bringing the stop 61 against the lug 60^a of the lever 60, where it is retained by the pawl 60^b; when the cam 105 drum is released from its driving worm 51 by depressing the treadle 57^a.

To determine the effective length of the cam 59, which must hold out the ring-winder clutch while the straight wire is being fed, 110 I provide the shipper slide 31 with a spring-pressed shoe 63, pivoted in a slot or recess formed in said slide, said shoe being thus adapted yieldingly to ride upon the cam drum 46 while secured against lateral movement relative to its slide, and to be engaged by the side face of the cam 59 to actuate said slide. Alongside the cam 59 is secured a short circumferentially adjustable switching-cam 65 (Figs. 9, 11 and 12) adapted to 115 lift the shoe 63 and permit the slide 31 to be shifted by its spring 31^a to throw in the clutch-member 30, the shoe 63 thereafter riding upon the cam 59, as shown in Fig. 9, to the end of said cam.

To assure that the sleeve 16^a (Fig. 7) when stopped, at the end of each complete operation, will have its radial slot in registry with that of the ring-winder 13, to permit removal of the work, I provide upon the 130

shaft 26 a pair of disks 66, 67 (Figs. 2 and 10), the former being secured to said shaft and the latter loosely journaled. Said disks are each provided with a stud, 68, 69, upon 5 their adjacent faces, anchoring the respective ends of a coiled spring 70 encircling the shaft 26. The disk 67 is formed with a notch 71 in its periphery adapted to receive a pawl 72 (Fig. 10), connected by a link 72^a with a lever 77 pivoted upon a bracket 77^b, said lever being adapted to be actuated by an electro-magnet 73 against the action of a spring 73^a to positively stop said disk when the normally open switch 46^c is closed by the cam 10 lug 46^b on the cam drum 46 (Fig. 7), while the disk 66 and shaft 26 continue to turn until stopped by the stress of the spring 70, the reaction of the spring 70 then turning the disk 66 and shaft 26 backward until the 15 stud 68 comes back into contact with the stud 69, thus stopping the sleeve 16^a with its slot in alignment with that of the ring-winder 13. With a spring of suitable strength the disk 66 turns through only a small arc after the 20 pawl 72 stops the disk 67 and the short return movement and consequent backward feeding of the wire-feeding rollers 15 (Fig. 1) does not excessively slack the wire anterior to said feed rollers.

30 An emergency stopping switch 74 and a starting switch 75 are conveniently positioned on the frame of the machine (Fig. 7), and 76 is a guard member secured to the lever 77, the latter being actuated by the 35 electro-magnet 73, said guard member thus being held over the starting switch 75 when the disk 67 is engaged by the pawl 72, to prevent the starting of the machine until said pawl has been withdrawn by the spring 73^a 40 upon the de-energizing of the electro-magnet 73 as hereinafter described.

The electric wiring system, diagrammatically shown in Fig. 3, comprises three incoming lines 78, 78^a, 78^b, of an alternating 45 three phase circuit, adapted to be connected with corresponding motor lines 79, 79^a, 79^b to the motor 84, by a self opening contactor switch 80 adapted to be closed by an electro-magnet 81.

50 z, z are wires connecting a single phase transformer 82 with the incoming lines 78, 78^b. The secondary y, y, of said transformer is branched; one branch thereof, x, x, x, connecting in series the electro-magnet 73 (Figs. 55 3, 7 and 10), and the normally open switch 46^c (Figs. 3 and 7). The other branch w, v, u, q, connects in series the electro-magnet 81, the normally closed stopping switch 46^c (Figs. 3 and 7), and the normally open 60 starting switch 75 (Figs. 3 and 7), while a branch therefrom, t, s, r, takes in the normally closed emergency stopping switch 74 (Figs. 3 and 7) and a switch 83 (Fig. 3) opening and closing with the motor switch 80, thus connecting them in series with the

electro-magnet 81 and the stopping switch 46^c and cutting out the starting switch 75.

It will be seen that this system is so arranged that the momentary closing of the starting switch 75 energizes the switch-closing electro-magnet 81, closing the motor switch 80 and also closing the switch 83, so that when the normally open starting switch 75 is released the current continues to pass through the electro-magnet 81 by way of wires w, v, u, t, s, r, until the circuit is broken by the momentary opening of the stopping switch 46^c, or the emergency stopping switch 74, whereupon the electro-magnet 81 is de-energized and the switch 83, with the motor switch 80, falls open. Closing of the switch 46^c energizes the electro-magnet 73 and thereby raises the pawl 72 into contact with the disk 67 to be engaged in the notch 71 thereof.

In the operation of the machine, the cam drum 46, being in starting position, with the driving clutch 27, 30 (Fig. 4) engaged and the stop 61 held between the lug 60^a of the lever 60 and the pawl 60^b (Fig. 1), the treadle 57 is released, allowing the spring 56^a (Figs. 1 and 7) to raise the worm 51 into mesh with the gear 50 and the lever 60 to disengage the stop 61. The starting switch 75 (Figs. 3 and 7) is then momentarily closed, whereupon the electro-magnet 81 (Fig. 3) closes the motor switch 80 and the switch 83 and continues to hold them closed after the starting switch 75 is allowed to re-open, the current passing from the wire u through the wires t, s, r instead of through the switch 75 and the wire q. The motor 84 then drives the ring-winder 13 and the sleeve 16^a counter-clockwise as viewed in Fig. 7, the latter at the higher speed.

By reason of the difference of the respective speeds of the ring-winder 13 and the sleeve 16^a, the wire-feeding rollers 15 carried by the ring-winder are driven, feeding wire through the die 17, and into the form 11, said wire being given a permanent helical form by its passage through said die while the ring-winder is turning. When a predetermined amount, usually six convolutions, of helical wire has thus been fed into the form, the cam 59 actuates the shipper slide 31, releasing the drive of the ring-winder 13, while the wire-feeding rollers 15 continue to be driven and, the wire beyond the die being prevented from turning on its axis, feed into the form 11 a length of straight wire predetermined by the setting of the stopping cam lug 46^b (Fig. 7), which upon reaching the stopping switch 46^c opens the latter, de-energizing the electro-magnet 81 (Fig. 3), and allowing the motor switch 80 and the switch 83 to fall open.

At approximately the time the clutch 27, 30 of the ring-winder is released, the inclined face 58^a of the cam 58 forces the lower

end of the lever 42 to the left as viewed in Fig. 7, tightening the brake-band 34, and shortly thereafter, the brake-band having slowed down the ring-winder, the side face 5 58^b of said cam forces the lower end of said lever to the right as viewed in Fig. 4, thereby throwing the roller 38 into the path of the brake-shoe 39 carried by the head 14^a and stopping said head and ring-winder in 10 the desired position, with the slot of the ring-winder within the gap of its support. With the construction shown, the action of the brake-shoe 39 upon the roller 38, by crowding the upper end of the lever 37 to 15 the right, as viewed in Fig. 7, further tightens the brake-band 34 immediately before said brake-shoe interposes the positive stop.

When the desired length of straight wire has thereafter been fed and the power has 20 been stopped as above described by the cam lug 46^b, said lug is carried sufficiently forward by the momentum of the cam drum 46 to contact the lever 46^c (Figs. 3 and 7), closing the switch 46^e and thus causing the pawl 25 72 to stop the disk 67, and by reason of the action of the spring 70 as above described, the sleeve 16^a is stopped with its slot in registry with that of the ring-winder 13. The form 11 is then opened, the wire severed 30 at an appropriate point in its straight length, and the work is removed.

The worm 51 is then thrown out of mesh with its gear 50 by means of the foot treadle 57^a, and the weight 46^d automatically turns 35 the cam drum 46 to starting position, or this may be done by turning the hand crank 49 if the weight 46^d is not used. As the drum is thus moved to starting position the shipper slide 31 is disengaged from the cam 59 40 by the switching cam 65 raising the shoe 63, and said shipper slide under pressure of its spring 31^a throws in the clutch 27, 30, while the general driving mechanism is stopped and the cam drum is running free thereof. 45 The treadle 57^a is then released, whereupon the worm 51 is again brought into mesh with its gear 50 by the spring 56^a, power is again applied through the shaft 18 by momentarily closing the starting switch 75, and 50 the operation is repeated.

The device preferably is adjusted for different sized grommets by shifting the stop 61 circumferentially upon the cam drum 46 to give the latter a different starting position, while the cam 59 may be left in the same position upon the drum and the stopping cam lug 46^b moved to give the desired length of straight wire after the ring-winder has been stopped by the cam 59 and the 55 brake mechanism. The device is thus subject to very minute adjustments and since the size of the grommet corresponds to linear measurements upon the cam drum the necessary adjustments readily may be calculated. The brake mechanism is accurately

effective and susceptible of very fine adjustment, and the machine is rendered almost entirely automatic.

The worm and worm-gear for driving the cam drum provide a sustained uniform 70 movement of the latter, as distinguished from the step-by-step movement imparted by the pawl and ratchet mechanism heretofore used, thereby facilitating the accurate timing of the several cams carried by the 75 drum. The worm and worm-gear are also preferable to other means for driving the drum in that, with a minimum of parts, they give the necessary slow speed, positive 80 drive, and facility of action in connecting the cam drum with and disconnecting it from the driving mechanism of the machine.

I claim:

1. In a gromet-winding machine, the combination of a slotted ring-winder, a 85 mounting therefor having a radial opening, a set of wire-feeding rollers carried by said ring-winder, a slotted driving member for said rollers journaled concentrically with said ring-winder, means for stopping said 90 ring-winder with its slot in registry with the opening of its mounting, and means for stopping said roller-driving member with its slot in registry with that of said ring-winder. 95

2. In a gromet-winding machine, the combination of a slotted ring-winder, a mounting therefor having a radial opening, a set of wire-feeding rollers carried by said ring-winder, a slotted driving member for 100 said rollers journaled concentrically with said ring-winder, means for stopping said ring-winder with its slot in registry with the opening of its mounting, and yielding means adapted to be brought into action 105 against said roller-driving member for stopping the latter with its slot in registry with that of said ring-winder.

3. In a gromet-winding machine, the combination of a slotted ring-winder, a 110 mounting therefor formed with a radial opening, a set of wire-feeding rollers carried by said ring-winder, a slotted driving member for said rollers journaled concentrically with said ring-winder, means for 115 stopping said ring-winder with its slot in registry with the opening of its mounting, a shaft adapted to drive said roller-driving member, a spring-anchoring member secured on said shaft, a spring-anchoring 120 member rotatably mounted on said shaft, a spring having its ends secured respectively to said spring-anchoring members, and means for stopping said rotatably-mounted member in such position that the force of 125 said spring will stop said shaft with the slot of said roller-driving member in registry with that of said ring-winder.

4. In a machine of the character described, the combination of a slotted ring- 130

winder, a mounting therefor formed with a radial opening, a set of wire-feeding rolls carried by said ring-winder, a slotted driving member for said rolls journaled concentrically with said ring-winder, means for stopping said ring-winder with its slot in registry with the opening of its mounting, yielding means for stopping said roller-driving member, said yielding means being 10 of sufficient reaction to turn said roller-driving member backward after stopping it, and means for positively stopping said roller-driving member in its backward movement with its slot in registry with that 15 of said ring-winder.

5. In a machine of the character described, the combination of a slotted ring-winder, a mounting therefor having a radial opening, a driving shaft for said ring-winder, a clutch 20 positioned operatively between said shaft and said ring-winder, a set of wire-feeding feed-rollers mounted on said ring-winder, a driving member for said feed-rollers journaled concentrically with said ring-winder 25 and adapted to be driven by said shaft, means for stopping said ring-winder with its slot in registry with the opening of its mounting, means for stopping said roller-driving member with its slot in registry with that of said ring-winder, and means for disengaging said clutch, actuating said ring-winder-stopping means and, at a stated interval thereafter, actuating said driving-member-stopping means.

35. 6. In a winding machine the combination of a slotted ring winder and a stop mechanism therefor, said stop mechanism comprising a friction brake member mounted upon a fixed part of the machine and a friction 40 brake member carried by a rotary part of the machine and adapted to coact with the first said friction brake member in a braking action during a part only of its revolution, so as to stop said ring winder in a 45 predetermined angular position.

7. In a winding machine the combination of a rotary spool-carrying member and a stop mechanism therefor, said stop mechanism comprising braking means mounted 50 upon a fixed part of the machine, and braking means carried by a rotary part of the machine and adapted to coact with the first said braking means in a braking action during a part only of the revolution of said 55 rotary member, said respective braking means being adapted to coact to produce a braking action of progressively increasing force and thereby to stop said spool-carrying member in a predetermined angular position.

60. 8. In a winding machine, the combination of a rotary member adapted to wind stranded material onto the work, a friction brake therefor adapted to brake said rotary member without regard to the angular position

of the latter, to lessen its speed, braking means adapted to act upon said rotary member only when the latter is in a predetermined part of its revolution, and a timing and controlling mechanism adapted to bring 70 said friction brake into operation first, to lessen the speed of said rotary member, and then to bring said braking means into operation, to stop said rotary member in a predetermined angular position. 75

9. In a winding machine, the combination of a rotary member adapted to wind stranded material onto the work, eccentrically-mounted braking means thereon, and braking means mounted upon a stationary part 80 of said machine and adapted to be brought into cooperation with said eccentrically-mounted braking means at a predetermined part of the latter's revolution, to brake and stop said rotary member. 85

10. In a winding machine, the combination of a rotary member adapted to wind stranded material onto the work, a friction-brake member carried thereby, and a friction-brake member mounted upon a stationary part 90 of said machine and adapted to be moved into the path of the first-said friction-brake member, said friction-brake members being so formed and positioned as to produce upon said rotary member a braking 95 action of progressively increasing force, and ultimately a positive stop.

11. In a winding machine, the combination of a rotary member adapted to wind stranded material onto the work, a friction-brake therefor, an eccentrically-mounted contact-member carried by a rotary part of said machine, a second contact-member adapted to be moved into the path of said eccentrically-mounted contact-member, and actuating means for said friction-brake so connected with the second contact-member as to be actuated thereby when said eccentrically-mounted contact-member contacts 105 said second contact-member. 110

12. In a winding machine, the combination of a rotary winder adapted to wind stranded material onto the work, a friction brake therefor, a brake lever for said friction brake, and a contact member eccentrically mounted on said winder and adapted to engage said brake lever to actuate said friction brake at a predetermined part of the revolution of said winder. 115

13. In a gromet-winding machine, the combination of a ring-winder, wire-feeding means on said ring-winder, a cam drum for controlling the action of said ring-winder and said wire-feeding means, a worm-gear adapted to drive said drum, a worm associated with said gear, and means for throwing said worm into and out of mesh with said gear to drive and release said drum. 120

14. In apparatus of the character described, the combination of a ring-winder, 130

5 a brake therefor, braking means adapted to act only when said winder is in a predetermined part of its revolution, and means connecting the two braking means for increasing the force of the former when the latter is in action.

10 15. In a machine of the character described, the combination of a ring-winder, wire-feeding means carried thereby and adapted to function while said winder is either in motion or stopped, a cam drum for timing the stopping of said winder and said wire-feeding means, means for driving said cam drum, means for freeing said cam drum from said driving means, means for turning said cam drum while so freed, and a stop member for stopping said drum in a predetermined position.

15 20. In apparatus of the character described, the combination of a ring-winder, a friction brake therefor, a supplemental brake mechanism adapted to bring said winder to a stop in a predetermined part of its revolution, a cam drum adapted to actuate said brake mechanisms, means for driving said drum, and means for freeing said drum from said driving means.

20 25. 17. In apparatus of the character described the combination of a ring-winder, a cam drum adapted to control the operation thereof, means for driving said drum, means for freeing said drum from said driving means, and means adapted automatically to turn said drum to a predetermined position when the latter is so freed.

25 30. 18. In apparatus of the character described the combination of a ring-winder, a cam drum adapted to control the operation thereof, means for driving said drum, means for freeing said drum from said driving means, means for turning said drum to a predetermined position when it is so freed, a driving clutch for said winder, a member adapted to be crowded by a cam on said drum to shift said clutch, and means upon said cam drum for subsequently moving said member in a different direction from that in which it is so crowded, to free it from the action of said cam.

30 35. 19. In a machine of the character described the combination of a ring-winder, a driving clutch therefor, a cam, a spring-projected member adapted to be crowded

55 by one face of said cam to shift said clutch, yielding means for urging said member in a direction parallel with said face, and means for lifting said member past said face against the action of said yielding means to permit said member to ride upon an adjacent face of said cam.

60 20. In apparatus of the character described, the combination of a ring-winder, a cam drum for controlling the operation thereof, means for driving said drum, means for freeing said drum from said driving means, and a weight mounted eccentrically upon said cam drum and adapted automatically to turn said drum to a predetermined position when the latter is so freed.

65 70. 21. In apparatus of the character described, the combination of a ring-winder, a cam drum for controlling the operation thereof, means for driving said drum, means for freeing said drum from said driving means, separate means for turning said drum when so freed, and means for positively stopping said drum in a predetermined position, the last said means being adapted to be moved respectively into 75 and out of operative position automatically when the drum is freed from its first mentioned driving means and re-engaged therewith.

75 80. 22. In a winding machine of the character described, the combination of a ring-winder, a cam drum for controlling the operation thereof, an eccentrically positioned weight on said drum, and means for stopping said drum in a predetermined position when 85 turned thereto by said weight.

85 90. 23. In a winding machine of the character described the combination of a ring-winder, wire-feeding means carried thereby, a common drive shaft for the two, a clutch interposed operatively between said shaft and said winder, a cam drum for timing the operation of said winder and said wire-feeding means, means for driving said drum, means for freeing said drum from said driving means, and means on said drum for stopping said drive-shaft.

95 100. In witness whereof I have hereunto set my hand this 8th day of September, 1921.

ROBERT C. PIERCE.
